UNITED STATES PATENT OFFICE.

FRANK VALENTA, OF PINEVILLE, MINNESOTA.

DESIGN FOR A TEETHING DEVICE.

52.087.

Specification for Design.

Patented June 4, 1918.

Application filed February 13, 1918. Serial No. 216,990. Term of patent 7 years.

To all whom it may concern:

Be it known that I, FRANK VALENTA, a citizen of the United States, residing at Pineville, in the county of Saint Louis and State of Minnesota, have invented a new, original, and ornamental Design for Teething Devices, of which the following is a specification, reference being had to the accompanying drawing, forming a part thereof.

The figure is a perspective view of a teething device showing my new design.

I claim:

The ornamental design for a teething device, as shown.

FRANK VALENTA.

Witnesses:

O. A. PANIER,
L. CHRISTOPHER.
